UNITED STATES PATENT OFFICE.

ENGELBRIGHT A. JOHANSON, OF SEATTLE, WASHINGTON.

DISH-WASHING MACHINE.

1,155,930.

Specification of Letters Patent.

Patented Oct. 5, 1915.

Application filed March 5, 1915. Serial No. 12,387.

To all whom it may concern:

Be it known that I, ENGELBRIGHT A. JOHANSON, a citizen of the United States, residing at Seattle, in the county of King and State of Washington, have invented certain new and useful Improvements in Dish-Washing Machines; and I do hereby declare the following to be a full, clear, and exact description of the invention, such as will enable others skilled in the art to which it appertains to make and use the same.

This invention relates to washing machines, and more particularly to a machine especially designed for washing dishes and the like.

The invention has for its object to provide a dish washing machine of novel and efficient construction including a cylinder and a brush arranged therein, and means for independently or simultaneously rotating the brush and cylinder.

With this and other objects in view, the invention consists in the novel construction, arrangement and formation of parts as will be hereinafter specifically described, claimed and illustrated in the accompanying drawing, in which

Figure 1 represents a perspective view, partly broken away, of the dish washing machine. Fig. 2 represents a longitudinal sectional view through the machine. Fig. 3 represents a transverse sectional view on the line 3—3 of Fig. 2. Fig. 4 represents a fragmental perspective view of one of the cylinders removed. Fig. 5 represents a perspective view of one of the cylinder supports and holders removed. Fig. 6 represents a front elevation of the brush and holder removed, and Fig. 7 represents a perspective view of an article holder removed.

Referring to the drawing in detail, wherein similar reference numerals designate corresponding parts throughout the several views, the numeral 10 indicates a liquid container of suitable size and shape having a centrally disposed and transversely extending partition 11 therein dividing the container into two compartments or chambers 12 and 13. The front wall of the compartment 12 is formed with an opening receiving a bushing or sleeve 14 in which is rotatably mounted a second sleeve 15, and a shaft 16 is rotatably mounted within the sleeve 15. The inner extremity of the sleeve 15 is preferably

squared to fit within the correspondingly shaped central aperture formed in a circular plate 17 constituting the front end wall of a perforate cylinder 18. The plate 17 is formed with a semi-circular flange 19 on which the adjacent end of the cylinder 18 is supported, the latter being provided with a pair of diametrically opposed shoulders 20, one of which engages under the angular or hooked end 21 of the flange 19, the other being engaged under a spring latch 22 secured to the end of the semicircular flange 19 opposite the hooks 21. The rear extremity of the cylinder 18 is rotatably supported by a cross piece 23 carrying a stub shaft 24 rotatably mounted in a bearing 25. The cylinder 18 is formed with a plurality of relatively small openings through which the water in the chamber 12 may flow and is also formed with a relatively large opening 26 through which dishes or other articles are positioned within or removed from the cylinder.

A hand crank 27 is removably secured to the outer extremity of the shaft 16 and is formed with a longitudinal slot 28 in which is slidably mounted a key 29 having a knob 30 at one end whereby the key may be moved longitudinally with relation to the crank arm 27. An arm 31 is secured to the forward extremity of the rotatable sleeve 15 and is formed in its outer end with a recess 32 adapted to receive the key 29 when the hand crank 27 and arm 31 are moved into alignment and the key is slipped inwardly within the slot 28.

A circular plate 34 is formed with a rectangular opening receiving the inner extremity of the shaft 15 and is provided upon the inner face with a pair of parallel flanges constituting holders 35 for a brush 36 slidably mounted between the holders 35.

A plate 37 is removably engaged against the front face of the strip 23 and carries a spring 38 extending longitudinally within the cylinder 18 and carrying a follower 39 at its forward extremity adapted to engage and retain plates or similar articles in operative engagement with the bristles of the brush 36.

When the key 29 is disengaged from the recess in the extremity of the arm 31 rotational movement of the hand crank 27 is imparted to the brush 36 through the shaft 16 and plate 34, the brush rotating upon the

plate 40 and thus reliably cleansing the latter.

When it is desired to simultaneously rotate the brush and the cylinder the arm 31 is moved into alignment with the hand crank 27 and the key 29 is slipped inwardly to engage within the recess 32, thus locking the shaft 16 and the sleeve 15 against relative rotation. A shaft 42 is rotatably mounted 10 in the front wall of the chamber 13 and removably supports a circular plate 43 at its rear extremity. The plate 43 is formed with a semi-circular flange identical with the flange 19 and supports a washing and rinsing cylinder 44 having a strip 45 secured diametrically across its rear end and carrying a stub shaft 46 rotatably mounted in a suitable bearing member 47 secured to the rear wall of the container 10.

20 It will be understood that the rinsing and washing cylinder 44 may be quickly and easily removed as is the first mentioned cylinder 18. An opening is formed in each of the end walls of the chambers 12 and 13 25 and cocks 48 are secured in said openings for draining the water from the chambers. A pulley 49 is keyed upon the forward extremity of the shaft 42, and a second pulley 50 is keyed to the sleeve 15, the pulleys 49 30 and 50 being connected by a belt 51, whereby rotational movement of the sleeve 15 is imparted to the shaft 42 and cylinder 44.

A plurality of radially disposed strips 52 are secured to the inner surface of the washing and rinsing cylinder 44 and are adapted to receive and hold cups and similar articles. The type of article holder illustrated in detail in Fig. 7 is especially designed for containing small dishes, knives, forks, spoons, 40 etc., and is adapted to be removably positioned within the rinsing cylinder 44. The holder 54 includes two substantially semi-circular end walls 55 and is formed with an opening 58 adapted to be closed by 45 a hinged door 59 preferably formed of wire mesh and hinged to one of the longitudinal edges of the openings 58 at 60. A compartment 61 is formed in the holder 54 for containing knives, forks and similar articles 50 and the compartment is adapted to be closed by a hinged door 62 also formed of wire mesh.

What I claim is:

1. A washing machine including a liquid 55 container, a cylinder rotatably mounted in said container, and a brush rotatably mounted in said cylinder.

2. A washing machine including a liquid 60 container, a cylinder rotatably mounted in said container, means for rotating said cylinder, and a brush rotatably mounted in said cylinder.

3. A washing machine including a liquid 65 container, a cylinder rotatably supported in said container, means for rotating said cyl-

inder, a brush rotatably mounted in said cylinder, and means for securing said brush for rotation with said cylinder.

4. A washing machine comprising a liquid 70 container, a cylinder rotatably mounted in said container, means for rotating said cylinder, a brush rotatably mounted in said cylinder, and means connecting said brush with said cylinder rotating means.

5. A dish washing machine comprising a liquid 75 container, a cylinder rotatably mounted in said container, a brush rotatably mounted in said container and projecting into said cylinder, and means for rotating said brush independently of said cylinder. 80

6. A washing machine comprising a liquid 85 container, a cylinder rotatably mounted in said container, a brush arranged within said cylinder and rotatably supported within said container, means for rotating said brush independently of said cylinder, and means for connecting said cylinder with said brush rotating means.

7. A washing machine comprising a liquid 90 container, a sleeve rotatably mounted in said container, a shaft rotatably mounted in said sleeve, means for rotating said shaft, means for connecting said shaft for rotation with said sleeve, a cylinder connected with said sleeve, and a brush arranged in 95 said cylinder and connected with said shaft.

8. A washing machine comprising a liquid 100 container, a sleeve rotatably mounted in said container, a shaft rotatably mounted in said sleeve, a hand crank carried by said shaft, an arm carried by said sleeve having a recess in the outer end thereof, a key slidably secured to said hand crank and movable into said recess to lock the shaft for rotation with the sleeve, a cylinder connected with said sleeve, and a brush removably secured to said shaft. 105

9. A washing machine including a liquid 110 container, a cylinder rotatably supported in said container, a brush rotatably mounted in said cylinder, and a spring actuated follower removably positioned within said cylinder and operable against said brush.

10. A washing machine comprising a liquid 115 container, a sleeve rotatably mounted in said container, a circular plate secured to the inner end of said sleeve, a semi-circular flange on said plate, a perforate cylinder supported at one end upon said semi-circular flange, means for securing said cylinder upon said flange, and means for rotatably supporting the opposite end of said cylinder.

11. A washing machine including a liquid 120 container, a sleeve rotatably mounted in said container, a circular plate secured to the inner extremity of said sleeve, a flange carried by said plate having one end hooked, a cylinder disposed on said flange, shoulders on said cylinder adapted to engage the hooked 125 130

end of said flange, means at the opposite end of said flange to lock the end of said cylinder thereon, and means for rotatably supporting the opposite end of said cylinder.

12. A washing machine including a liquid container, a sleeve rotatably mounted in said container, a circular plate secured to the inner end of said sleeve, a semicircular flange carried by said plate having one end hooked, a cylinder, a pair of diametrically opposed shoulders on said cylinder, one of

said shoulders being engaged under the hooked end of said flange, a spring latch secured to the opposite end of said flange 15 adapted to engage behind the other shoulder, and means for rotatably supporting the opposite end of said cylinder.

In testimony whereof I affix my signature in presence of two witnesses.

ENGELBRIGHT A. JOHANSON.
